FIG. 1

FIG. 2

FIG. 3

INVENTOR
RUSSELL G. THOMPSON
BY
Harold E. Stonebraker,
ATTORNEY

UNITED STATES PATENT OFFICE

RUSSELL G. THOMPSON, OF ROCHESTER, NEW YORK, ASSIGNOR TO ELECTROMATIC TYPEWRITERS, INC., OF ROCHESTER, NEW YORK, A CORPORATION OF NEW YORK

TYPEWRITING MACHINE

Application filed March 5, 1931. Serial No. 520,222.

This invention relates to improvements in typewriting machines, and particularly to keys for such machines. It is the common practice in mounting the keys on the key levers to form the keys with tapered openings and pressing them into frictional engagement with a projection on the key lever. This practice causes the key to expand more or less and results in breaking the walls of a large number, rendering them useless, since they will not firmly engage the key. It is the object of this invention to provide a key with means for reinforcing its side walls so that it can be pressed on the key lever without danger of breaking or splitting its side walls.

More specifically, it is the object of this invention to provide a key for typewriting machines having a ring embedded in its side walls for protecting said walls against breakage.

To these and other ends, the invention consists in the construction and arrangement of parts that will appear from the following description when read in conjunction with the accompanying drawing, the novel features being pointed out in the claims following the specification.

In the drawing:

Fig. 1 is a side elevation of a typewriter key lever showing a key in vertical section mounted thereon and illustrating one embodiment of the invention;

Fig. 2 is an enlarged vertical section of the key, and

Fig. 3 is an inverted plan view of the same. Referring particularly to the drawing, 1 is a key lever of usual or well known construction having an upwardly projecting arm 2 at or adjacent its front end, terminating in a lug 3. The front and rear edges 4 and 5 of the lug 3 are inclined upwardly and meet a horizontal edge 6 at their upper ends. At their lower ends, the edges 4 and 5 terminate in horizontal shoulders.

The key comprising a body portion 7 is cast or molded of suitable material, such as bakelite, of circular form, as shown in Fig. 3, and enlarged at its top to form a finger piece. From the circumference of the top it tapers

inwardly and downwardly, having a plane surface 8 at its lower side. It is formed with an upwardly extending slot 9 from said lower side, said slot being of a breadth substantially equal to the thickness of the material of which the lug 3 is formed. The front and rear walls of the slot are inclined or tapered toward each other so that the opening 9 in the key conforms generally to the shape of the lug 3, although its front and rear walls are somewhat nearer together so that when the key is pressed on the lug, it is permanently secured thereto by its frictional engagement therewith.

The frictional engagement of the key with the lug, when the key is pressed on the lug, has a tendency to expand the key and often results in breaking or cracking its thinner walls surrounding the opening 9. It is therefore desirable to reinforce the walls of the key, particularly at and adjacent the lower end of the opening 9 where they are weakest and there is greatest liability of breaking. To this end, a ring 10 of suitable material, such as iron or brass, is cast or otherwise secured in the wall of the key and arranged to entirely surround the opening 9 therein. By this arrangement, the ring is substantially concentric with the key so that it serves to reinforce the wall of the key around the opening or slot 9.

A key thus constructed may be made at but little extra expense and efficiently reinforces the walls of the key, eliminating possibility of breakage when the key is pressed on the key lever.

Although only one embodiment of the invention is shown and described herein, it will be understood that this application is intended to cover such changes or modifications as come within the spirit of the invention or scope of the following claims.

I claim:

1. In a typewriting machine or the like, the combination of a key lever, a projecting lug on said key lever, a key constructed of frangible material and having an opening therein whereby it is frictionally engaged with said lug when pressed thereon, and a ring embedded in the wall of said key and

surrounding said opening for reinforcing the wall of said key.

2. In a typewriting machine or the like, the combination of a key lever, a lug having tapered sides on said key lever, a key constructed of frangible material and having an opening therein provided with inclined walls corresponding to the tapered sides of the lug whereby it is frictionally engaged with the lug when pressed into engagement therewith, and a ring arranged in said key around said opening for reinforcing its walls.

3. A key for typewriters or the like constructed of frangible material and comprising a body having a finger piece at its top and an opening in its bottom, and a reinforcing ring embedded in the material of said body and surrounding the lower end of said opening.

4. A key for typewriters or the like constructed of frangible material and comprising a body enlarged at its top to form a finger piece and an opening in its bottom, said opening having inclined walls, and a reinforcing ring embedded in the material of said body and surrounding said opening.

In witness whereof, I have hereunto signed my name.

RUSSELL G. THOMPSON.
